RAILWAY TRAFFIC CONTROLLING
APPARATUSHoward A. Thompson, Edgewood, Pa., assignor to
The Union Switch & Signal Company, Swiss-
vale, Pa., a corporation of PennsylvaniaApplication February 12, 1935, Serial No. 6,174
Renewed May 29, 1936

2 Claims. (Cl. 246—34)

My invention relates to railway traffic controlling apparatus, and more specifically to apparatus for controlling wayside and/or cab signals by means of coded trackway energy.

- 5 One feature of my invention is the elimination, in apparatus of the above character, of all moving parts in the code following elements of the system such as, for example, the contacts of the usual code following track relay or of the locomotive-carried master relay. That is to say, in the system which I provide, decoding in the wayside equipment or aboard the locomotive is accomplished primarily by means of static apparatus, thus eliminating the mechanical and contact wear to which the usual continuously operating code following apparatus is ordinarily subjected. Other novel features of my invention will become apparent as the description progresses.
- 20 The railway traffic controlling apparatus set forth in my present application is somewhat similar to that set forth in the copending applications of Philip H. Dowling, Serial No. 532,028, filed on April 22, 1931, and Serial No. 219,243, filed on 25 July 14, 1938 (division of Serial No. 532,028), for Railway signaling systems, and the said copending applications contain claims which cover broadly certain features of the invention described in my present application.
- 30 I will describe one form of apparatus embodying my invention, and will then point out the novel features thereof in claims.

In the accompanying drawing, Fig. 1 is a diagrammatic view showing a stretch of railway track equipped with apparatus embodying my invention, which apparatus is adapted to be controlled in accordance with the usual "frequency" type of code. Figs. 1^a and 1^b are diagrammatic views showing in greater detail certain portions of the apparatus illustrated in Fig. 1.

40 Similar reference characters refer to similar parts in each of the foregoing figures.

Referring to Fig. 1 of the drawing, the reference characters 1 and 1^a designate the track rails of a stretch of railway track which is divided by insulated joints into a number of blocks of which but two blocks, 2—3 and 3—4, are shown. Traffic normally travels over this stretch of track from left to right, in the direction of the arrow. 45 Traffic entering each block is protected by a signal designated by the reference character S with a distinguishing exponent corresponding to the location. The block 2—3 is intersected by a highway and accordingly, a cut section is provided at 50 the highway location 2^a so that traffic passing

over the highway may be protected by the highway crossing signals XS.

At the leaving end of each track section is a track transformer TT which supplies coded alternating current to its associated section when traffic conditions in advance of the section are favorable. In the apparatus which is shown, but two codes are used, these being sufficient for the relatively simple form of two-block three-indication system illustrated. One of these codes is furnished by a constantly operating coding device or code transmitter CT—75 and, in the present embodiment, consists of alternating current which is periodically interrupted or varied at a constant rate, such for example, as 75 times per minute. This code is used to provide a "caution" or "Y" indication in the apparatus of Fig. 1. The "proceed" or "G" indication code is furnished by a similar constantly operating code transmitter CT—180 and consists of alternating current which is periodically interrupted at a different rate such as 180 times per minute. The code transmitters CT—75 and CT—180 are constantly supplied with current from a direct current source having the terminals B—C. It is obvious that these transmitters may be operated from an alternating current source if desired, and that instead of being constantly operated, they may be energized in any suitable manner at such times only as required by traffic conditions in the associated track sections. The selection of the code which is furnished to the track transformers TT is determined by traffic conditions in advance in a manner which will be clear from the description which follows.

35 Each track section is provided with what may be conveniently termed a track relay of the saturation type, designated by the reference character TR and designed in such a manner that the presence of a relatively small amount of direct current in a saturating or control winding of the relay causes a relatively large change in impedance of the main relay windings. In its essential elements this relay comprises a saturable core on which are wound a saturation or input 40 winding and an impedance or output winding. A relay of this type is described in the United States Patent No. 1,936,705, granted to H. D. Abernethy, for Automatic railway block signaling system.

45 Referring for the moment to Fig. 1^b, the track relay TR preferably comprises a three-legged magnetizable core on the central leg of which is mounted a control or saturation winding 5, and on the two outer legs of which are mounted the 50

55

main or impedance windings 6 and 7. The windings 6 and 7 are wound in such a direction as to set up opposing fluxes in the middle leg of the core, thereby preventing alternating current from being induced in the control winding 5. For some purposes, as will be explained hereinafter, additional impedance windings 24 and 25 may be used. The saturation relay AR illustrated in Fig. 1^a is similar to the track relay TR of Fig. 1^b, but dispenses with the additional windings 24 and 25.

Associated with each track relay of the apparatus shown in Fig. 1 is a relay transformer RT which insulates the winding 5 from the track rails, and a rectifier K which converts the coded alternating current received from the rails into pulses of unidirectional current in winding 5. Considering location 2, windings 6 and 7 of the track relay TR² are connected with an alternating current source having the terminals BX—CX, through the primary winding 8 of an auxiliary transformer AT². During the "on" period of the code, the rectified current in winding 5 saturates the core of relay TR² and allows alternating current to flow in the primary winding 8 of transformer AT². During the "off" period of the code, the control winding 5 receives no energy so that the windings 6 and 7 of relay TR² represent a high impedance in series with winding 8 of transformer AT² with the result that this transformer receives practically no energy during the "off" code period. It will be apparent from the foregoing, therefore, that transformer AT² will receive impulses of energy in step with the code being supplied to the track section 2—3.

The output of transformer AT² is rectified by the rectifier L² and is impressed across a portion of the winding of the decoding transformer DT². This decoding transformer furnishes energy to an untuned direct current relay H², which relay is energized through the secondary winding 9 of transformer DT² and a rectifier M². Relay H² is so designed that it will remain energized whenever transformer DT² is receiving impulses either of 75 or 180 code. The direct current decoding relay J² receives energy from a portion of the winding of transformer DT² and is connected through a decoding unit DU² of well-known type. The details of unit DU² are not shown but this unit usually comprises a rectifier and a reactor-condenser tuning unit for tuning relay J² whereby it will become energized on impulses of 180 code supplied to transformer DT², but will remain deenergized when the impulses received are of 75 code.

When relay H² is energized, direct current is supplied from the source having terminals B—C over the coding contact 13 of transmitter CT—180 and the front contact 14—15 of relay H², to the control winding 10 of the auxiliary saturation relay AR² at location 2. If relay H² is deenergized, direct current will be fed to winding 10 of relay AR² over the coding contact 17 of transmitter CT—75, and back contact 14—16 of relay H². The impedance windings 11 and 12 of saturation relay AR² are in series with the primary winding of transformer TT² and also in series with the alternating current source BX—CX, so that transformer TT² will receive code impulses in step with the impulses which are delivered to saturation winding 10. Therefore, when winding 5 of relay TR² is receiving either 180 or 75 code, relay H² will be energized and consequently 180 code will be supplied to the rails of the section in the rear of location 2. Sim-

ilarly, when winding 5 is not receiving code so that relay H² is deenergized, 75 code will be supplied, in like manner, to the rails of the rear section.

Referring now to the cut section location 2^a, the track relay TR^{2a} is provided with additional windings 24 and 25 for the purpose of controlling a clearing-out relay F^{2a} which controls the operation of the protective apparatus at the highway crossing. Relay F^{2a} is controlled through a transformer T^{2a} and a rectifier N^{2a}, and is designed to remain energized whenever winding 5 of relay TR^{2a} is receiving code. The track relay TR^{2a} serves to repeat the code which it receives, to the section in the rear, so that whatever code is supplied to section 2^a—3, this same code will be repeated into the rear section 2—2^a.

Having described the various elements of the system individually, I shall now explain the operation of the system as a whole. In doing this, I shall assume that a train enters the section 2—2^a from the left, the remaining sections in advance being unoccupied. Just prior to the entry of the train, sections 2—3 and 3—4 will both be receiving 180 code and the respective relays H and J at locations 2 and 3 will all be energized so that the signals S will indicate proceed. The circuit for the G lamp of signal S² includes front contact 18—22 of relay H² and front contact 19—20 of relay J². Similar circuits will be effective for energizing signals S³ and S⁴. As soon as the train enters section 2—2^a, energy will be cut off from winding 5 of relay TR² so that transformers AT² and DT² will become effectively de-energized and will cause both decoding relays H² and J² to release. Signal S² will now indicate "R" over the back contact 18—23 of relay H². At the same time, due to the entry of the train into section 2—2^a, relay F^{2a} will become deenergized and will open its front contact 26 to deenergize the left-hand winding of the highway crossing relay XR. In this manner, operation of the crossing signals XS will be initiated with the entry of the train into the section.

When the train progresses beyond location 2^a, winding 5 of relay TR^{2a} will be deprived of current so that the clearing-out relay F^{2a} will be deenergized and will close its back contact 27, opening its front contact 28. The closing of back contact 27 causes steady or uncoded alternating current energy to be supplied to track transformer TT^{2a} for the purpose of causing energization of relay F². As soon as the train has completely vacated section 2—2^a, sufficient energy will be received by relay F² due to the lowered impedance of windings 24 and 25 of relay TR² to cause front contact 26 to close, thereby energizing the left-hand winding of relay XR to restore the signals XS to the inoperative condition.

Nothing further happens until the train enters section 3—4. When this occurs, relays H³ and J³ will both release and section 2^a—3 will be supplied with current of 75 code over a circuit which will be clear from the description previously given. As soon as the train completely vacates section 2^a—3, track relay TR^{2a} will respond to the 75 code current in its saturation winding 5 and relay F^{2a} will become energized, thus opening back contact 27 to remove steady energy from the section 2—2^a. The 75 code will be repeated from section 2^a—3 into the rear section 2—2^a and will cause relay H² to become energized. Signal S² will now indicate "Y", over the front contact 18—22 of relay H² and the back contact 75.

19-21 of relay J². Under this condition, 180 code will be supplied to the section in the rear of section 2-2^a.

When the train vacates section 3-4, current of 5 75 code will be supplied to this section to energize relay H³ whereby current of 180 code will be supplied to the two track circuits of section 2-3. Signal S² will now indicate "G". When the train completely vacates the section in advance of location 10 4, section 3-4 will also receive 180 code, so that signal S³ will indicate "G" and all the apparatus of Fig. 1 will be restored to the condition in which it is illustrated.

The purpose served by front contact 28 of relay F^{2a} is to provide for initiating the operation of the crossing signals XS as soon as a train traveling in a direction opposed to that indicated by the arrow passes location 3. This is accomplished by the deenergization of the right-hand winding of the crossing relay XR, which relay will set the crossing signals into operation by means of circuits which are well known and which it is unnecessary to describe in detail.

It will be understood that relays F² and F^{2a} 25 may be of the alternating current type, in which case the respective transformers T² and T^{2a}, and rectifiers N² and N^{2a} may be eliminated. The use of direct current relays which are energized from rectifiers has the advantage that slow acting characteristics are more readily obtainable 30 with this combination than if alternating current relays are used.

The system disclosed is also applicable to direct current track circuits, in which case the 35 transformers RT and rectifiers K may be eliminated, the control winding 5 of the track relays TR being connected directly with the track rails.

It will be clear that the system disclosed is not limited to track circuits of the coded rail current 40 type, as a two-indication system may be provided by using steady or uncoded current in the rails. In such case, relays H may be energized directly from the rectifiers L, eliminating the decoding transformers DT and rectifiers M. Furthermore, 45 if coded track circuits are used, any suitable type of code such, for example, as the "time" or "pattern" code, or the "count" code may be used, the system being not limited to the "frequency" type of code which has been used for purposes 50 of illustration only.

Although the system disclosed shows the control of wayside equipment only, it will be readily

apparent that the apparatus can also be used to control locomotive cab signaling equipment. In such case, the control winding of the saturation relay on the locomotive will receive its saturation energy inductively from the rails by means of receiving equipment which is well-known in the art, and the saturation relay will be used to control cab signals in a manner similar to that disclosed in connection with the control of the wayside signals S in Fig. 1.

Although I have shown and described but one form of apparatus embodying my invention, it is understood that various changes and modifications may be made therein within the scope of the appended claims without departing from 15 the spirit and scope of my invention.

Having thus described my invention, what I claim is:

1. In combination, a first and a second section of railway track, means for supplying coded current to the rails of said first section, a saturation relay comprising a magnetizable core having an input winding receiving coded energy from the rails of said first section for changing the flux in said core in step with said coded energy and having a first and a second output winding on said core, means including said first output winding for at times supplying coded current to the rails of said second section, a normally energized relay receiving energy at said times from 30 said second output winding, and means effective when said last mentioned relay is deenergized for supplying uncoded current to the rails of said second section.

2. Decoding means for coded A. C. track circuits comprising a rectifier receiving energy from the track rails of a given section, a transformer, a decoder including relays selectively responsive to the periodicity of energization of said transformer, a local source of current for energizing 40 said transformer, means including a voltage responsive device all of the component parts of which are stationary, said device being responsive to a difference of potential supplied by said rectifier, for controlling the energization of said 45 transformer from said local source, and means controlled by one of said decoding relays and including a saturable device all of the component parts of which are also stationary for supplying current to the track rails in the rear of 50 said given section.

HOWARD A. THOMPSON.
